UNITED STATES PATENT OFFICE.

HERMAN H. JUERGENS, OF FORT WAYNE, INDIANA.

TRUCK.

1,146,077.

Specification of Letters Patent. Patented July 13, 1915.

Application filed September 12, 1913. Serial No. 739,488.

To all whom it may concern:

Be it known that I, HERMAN H. JUERGENS, a citizen of the United States, residing at Fort Wayne, in the county of Allen and 5 State of Indiana, have invented new and useful Improvements in Trucks, of which the following is a specification.

This invention has relation to trucks adapted to be used for moving baggage and 10 express matter and it consists in the novel features hereinafter described and claimed.

An object of the invention is to provide a truck of the character indicated having its parts so arranged that the platform of the 15 truck may be readily raised or lowered.

With the above object in view the truck comprises a platform having brackets pivotally connected with the opposite end portions thereof. The said brackets being provided with shoulders. Stops are mounted at the under side of the platform in the path 20 of movement of the shoulders and are adapted to be engaged by the same when the said brackets are directly under the platform. Ground wheels are journaled to the 25 brackets. A shaft is journaled for rotation under the intermediate portion of the platform and carries a winding drum about which is wound two cables. Means is provided for turning the shaft and the cables are trained over suitable pulleys and connected with the brackets so that as the shaft 30 is rotated the brackets are swung simultaneously away from each other or toward each other. As the brackets move away from each other the platform lowers and as the brackets move toward each other the platform is elevated.

In the accompanying drawing:—Figure 1 40 is a side elevation of the truck. Fig. 2 is a bottom plan view of the same. Fig. 3 is an end elevation of the same. Fig. 4 is a transverse sectional view of the same cut on the line $x-x$ of Fig. 2. Fig. 5 is a plan view 45 of a drum and adjacent parts used upon the truck.

The truck comprises a platform 1 to the end portions of which are pivotally attached brackets 2. The brackets 2 are provided at 50 their inner sides with shoulders 3 which are adapted to encounter stops or legs 4 attached

to the platform when the said brackets are completely under the platform. Wheels 5 are journaled to the brackets and the brackets 2 are provided at their inner sides with 55 cable guides 6.

A shaft 7 is journaled for rotation under the intermediate portion of the platform 1 and a drum 8 is mounted upon the said shaft. Cables 9 and 10 are wound about the 60 drum and are so arranged that as one end portion of the cable is wound upon the drum the other end portion thereof unwinds from the same and vice versa. One run of each of the cables 9 and 10 extend directly from the 65 drum 8 to one of the brackets 2 and the other run of the said cables is trained over a pulley 11 journaled at the end portion of the platform 1 and then extends down and is secured to the lower portion of the adjacent bracket 2. A worm wheel 20 is fixed to the shaft 7 and a worm 13 mounted on a shaft 14 engages the said worm wheel. The shaft 14 is journaled for rotation under the 70 platform 1 and extends beyond one end 75 thereof and a crank handle 15 may be applied to the projecting end portion of the said shaft. Therefore it will be seen that by turning the shaft 7 and drum 8 the brackets 2 may be swung from under the platform 1 whereby the said platform may be lowered. After the platform has been lowered it may be loaded with articles and when 80 it is desired to transfer the articles from the truck to a car or other vehicle the shaft 85 7 and drum 8 may be turned whereby the brackets 2 are drawn back under the platform 1 and the said platform is elevated. Thus the articles upon the platform are 85 raised and may be readily shifted from the 90 platform to the floor of the car.

Having described the invention what is claimed is:

1. A truck comprising a platform, brackets pivoted to the platform, wheels journaled 95 to the brackets, a drum journaled upon the platform, a cable connected at both of its ends with each bracket and the intermediate portions of all of the cables arranged to wind upon the drum.

2. A truck comprising a platform, brackets pivoted to the platform, cable guides car-

ried by the brackets, wheels journaled to the brackets, a drum journaled for rotation under the platform, a cable connected at both of its ends with each bracket and the intermediate portions of all of the cables arranged to wind upon the drum, said cables engaging said cable guides.

In testimony whereof I affix my signature in presence of two witnesses.

HERMAN H. JUERGENS.

Witnesses:

NAT D. HULL,
GLENN A. SMILEY.
